FASTENING-INSERTING MACHINE

Jacob C. Jorgensen, Beverly, Mass., assignor to
United Shoe Machinery Corporation, Borough
of Flemington, N. J., a corporation of New
Jersey

Application October 15, 1937, Serial No. 169,219

9 Claims.

(Cl. 1—6)

This invention relates to fastening-inserting machines and is herein illustrated as applied to a heel-end lasting machine having means for driving a row of tacks around the heel end of the bottom of a shoe to fasten the upper in lasted position. It is to be understood, however, that the invention is not limited to lasting machines or to machines that operate on the heel ends of shoes.

10 Heel-end lasting machines constructed, for example, as disclosed in United States Letters Patent No. 2,059,241, granted on November 3, 1936 upon an application of mine, are provided with a row of tacking devices movable with the heel-end 15 wipers for driving a row of tacks around the heel seat to fasten the overwiped margin of the upper, and with means for delivering the tacks to these devices from a plurality of raceways through tubes which lead respectively to the different devices. In view of the large number of tacks which 20 it is desirable to drive in each shoe, there are conveniently provided half as many raceways as tacking devices, a separator which receives two operative movements in each cycle of operations 25 of the machine to separate two sets of tacks from the raceways, and a member which receives the two sets of tacks and delivers them into the appropriate tubes. Each raceway thus supplies tacks to two of the tacking devices in the operation 30 of the machine on each shoe.

In operating on shoes of different sizes with a machine of the above-mentioned character it is desirable to vary the number of tacks driven by the machine. In operating on some shoes, for 35 example, the tack at each end of the row should be omitted, and in operating on still smaller shoes it is desirable to dispense with two or three tacks at each end of the row. The construction herein shown is such that variation in the number of 40 tacks driven may be quickly and easily effected. For the purpose in view, tubes leading to tacking devices which occupy analogous or corresponding positions at or near the opposite ends of the row of devices are arranged to receive tacks supplied 45 from the same raceway. That is, as herein illustrated, the tubes leading to the two devices at the opposite ends of the row receive tacks from one raceway, the two devices next in line receive tacks from another raceway, and the two devices 50 which are third from the opposite ends of the row receive tacks from still another raceway. If it is desired, therefore, to omit the two tacks at the opposite ends of the row, this may be accomplished simply by preventing delivery of tacks 55 from one raceway, and similarly tacks normally

driven by other devices in corresponding locations near the opposite ends of the row may be omitted by preventing delivery of tacks from one or more additional raceways. The invention provides novel means for thus preventing delivery of tacks, the construction shown comprising a plurality of raceway-closing fingers associated respectively with the different raceways and movable as a unit by a controlling member to close or to open all the raceways when desired, as heretofore, together with means whereby one or more of the fingers may be maintained in position to prevent delivery of tacks regardless of movements of the other fingers by the controlling member.

The above and other features of the invention, including various novel details of construction and combinations of parts, will now be more particularly described with reference to the accompanying drawings and thereafter pointed out in the claims.

In the drawings,

Fig. 1 is a perspective view of a portion of a machine in which the invention is embodied, with parts broken away;

Fig. 2 is a view partly in right-hand side elevation and partly in section of tack-supplying mechanism shown in Fig. 1, a portion of this mechanism being sectioned along the line II—II of Fig. 3;

Fig. 3 shows a portion of the mechanism for preventing delivery of tacks from the raceways, as viewed in the direction of the arrow on Fig. 2;

Fig. 4 is a perspective view on a larger scale of a portion of the structure shown in Fig. 3, with a part in section along the line IV—IV of Fig. 3 and other parts broken away; and

Fig. 5 is a vertical sectional view of tacking mechanism shown in Fig. 1 and other parts of the machine associated therewith.

The invention is herein illustrated as applied to a machine of the character fully disclosed in the above-mentioned Letters Patent, and only such parts of the machine therefore as it is necessary to refer to for an understanding of the invention are hereinafter mentioned. The machine includes a pair of wipers 2 (Figs. 1 and 5) which are movable lengthwise and laterally of the shoe to wipe the margin of the heel end of the upper inwardly over an insole on the last, the last and shoe being mounted on a work support 4 and clamped about the heel end by a heel band 6. Secured respectively to the different wipers to move therewith are two tacker blocks 8 curved similarly to the wipers, these blocks cooperating with other parts to provide a row of tacking devices for driv-

ing a row of tacks around the heel seat to fasten the overwiped margin of the upper in lasted position. Each tacking device, as illustrated in Fig. 5, comprises a spring-controlled finger 10 which 5 cooperates with a flange 12 on the corresponding wiper 2 to provide a tack pocket in which a tack is supported in position to be driven through an opening 14 in the wiper, and a driver 16 for driving the tack, the several drivers associated 10 with each wiper being fastened to a driver block 18 which is movable vertically in a guideway in the tacker block 8. The two driver blocks 18 are operated by a member 20 connected to them in such manner as to permit them to move with the 15 wipers.

The tacks are delivered to the tacking devices through a plurality of flexible tubes or conduits 22 which lead respectively to the different devices, the lower ends of these tubes being mounted 20 in openings in the tacker blocks 8. The tacks are supplied by a plurality of inclined raceways 24 from the lower ends of which they are separated and delivered by a reciprocatory separator 26. From the separator the tacks fall into openings 28 in a removable end block 30, these openings communicating with other openings 32 provided in a raceway-supporting plate 34. Only one of the openings 28 and the opening 32 associated therewith are shown in the drawings, but 30 it will be understood that a pair of such openings 28 and 32 is provided for each raceway. In view of the large number of tacks which it is desirable to drive in a machine of the character illustrated, it is preferable, as shown, to provide only half as 35 many raceways as tacking devices, and accordingly the separator 26 receives two operative movements in each cycle of operations of the machine to separate two sets of tacks from the same raceways to be delivered respectively to 40 different groups of tacking devices. In order to distribute the two sets of tacks to the proper tacking devices there is provided a reciprocatory receiving slide 36 which receives the tacks from the openings 32 in the plate 34 and delivers them 45 into the proper tubes 22 through passageways 38 in a member 40 to which the upper ends of the tubes 22 are connected. The receiving slide 36 has, for each raceway, a pair of passageways 42 which, through movements of the slide, com- 50 municate successively with the corresponding opening 32 in the plate 34 to receive the two tacks delivered successively from the same raceway by the separator 26, these passageways being arranged to deliver the tacks into the appropriate 55 passageways 38 in the member 40 and thus into the tubes 22 communicating with the passageways 38. The construction of the tack-supplying mechanism as thus far described will be more fully understood by reference to United States 60 Letters Patent No. 1,933,594, granted on November 7, 1933 upon an application of mine.

Lasting machines of the character illustrated are used to last shoes of different sizes, and it is accordingly desirable to vary the number of tacks 65 driven by the machine. That is, in operating on some shoes it is desirable to omit the tack which would be driven by each of the two endmost tacking devices of the row of devices, and in lasting still smaller shoes two or three tacks at each 70 end of the row should be omitted. As herein shown, therefore, the tack-delivering tubes 22 are so arranged that the two tubes *a* leading to the two endmost tacking devices, i. e., the two devices located farthest from the extreme heel 75 end of the shoe, are arranged to communicate

at their upper ends with two passages 38 in the member 40 which are supplied with tacks from the same raceway, this raceway in the construction shown being the middle one of the group of eleven raceways. Similarly the two tubes *b* leading to the tacking devices next in line are, as illustrated, arranged to receive their tacks from the raceway next at the right of the middle raceway, and the two tubes *c* leading to the devices which are third from the opposite ends of the row are arranged to receive tacks from the raceway located next at the left of the middle raceway. Accordingly, if it is desired to omit the two tacks at the opposite ends of the row, this may be done simply by preventing separation of 15 tacks from the middle raceway. The second tack from each end of the row, moreover, may be omitted by preventing separation of tacks from the raceway at the right of the middle raceway, and the two tacks which are third from the opposite ends of the row may be omitted by preventing separation of tacks from the raceway at the left of the middle raceway. It will be understood that the machine might also include provision for similarly omitting additional tacks, but in practice it 20 has been found that there is ordinarily no necessity for omitting more than the three tacks at each end of the row.

For conveniently preventing, when desired, the separation of tacks from one or more of the three above-mentioned raceways the construction herein shown comprises a modification of mechanism heretofore provided for preventing at will the delivery of tacks from all the raceways, so 30 that the separator may be removed without releasing the rows of tacks, as disclosed in United States Letters Patent No. 2,047,205, granted on July 14, 1936 upon an application of mine. In that mechanism, as in the mechanism herein shown, a shaft 44 extending transversely of the 40 raceways is supported by a fixed cover 46 mounted over portions of the raceways and is rotatable about the same axis as a movable cover 43 which, when in operative position, extends over the lower end portions of the raceways and over the separator 26, this movable cover being shown in Figs. 1 and 2 of the drawings in its upturned position. The shaft 44 is rotatable by means of a small hand wheel 50 on one end thereof and has fast thereon, as heretofore, a plurality of 50 raceway-closing fingers 52 associated respectively with all the raceways except, in the construction herein shown, those three from which tacks are supplied to the three pairs of tubes *a*, *b* and *c*. The shaft extends through these fingers and they 55 are permanently locked to it in alignment with one another by engagement with a flat face 54 (Fig. 4) on the shaft, the fingers being properly spaced from one another by collars 56 on the shaft. Accordingly, when the shaft is turned in 60 one direction, with the cover 46 in its lowered position, these fingers are swung as a unit downwardly into the raceways and by engagement with the endmost tacks move the several rows of tacks somewhat upwardly along the raceways and thereafter prevent any further delivery of tacks from the raceways as long as the fingers remain 65 in operative positions. For purposes of this invention there are associated with the raceways which supply tacks to the tubes *a*, *b* and *c* three 70 fingers 58 which may be locked to the shaft 44 in alignment with the fingers 52 to move with the latter as heretofore when it is desired to close or open all the raceways, or may be unlocked 75 from the shaft, each independently of the others, 75

to permit one or more of them to be maintained in position to prevent delivery of tacks regardless of rotation of the shaft 44. Associated with each of these fingers at the right thereof is a spacing 5 collar 60 which, as distinguished from each of the collars 56, has a reduced end portion upon which the finger is mounted, and slidably movable in a guideway in each of these collars, along the flat face 54 of the shaft, is a block 62 arranged to enter a correspondingly shaped opening 64 in the finger 58 associated therewith to lock the finger to the shaft in alignment with the fingers 52. When the block is moved lengthwise of the shaft to withdraw it from the opening 64 in the finger, the finger may be swung by the operator about its bearing on the collar 60 into position to enter the corresponding raceway and retract the row of tacks. Each finger 58 has a lug 66 thereon to assist the operator in swinging it out of the raceway when it is desired thereafter to open the raceway. Each block 62 is provided with a pin 68 extending through a slot 70 in the collar 60 for use in sliding it into or out of position to lock the finger which it controls in fixed relation 20 to the shaft 44. Associated with each of the three fingers 58 is a resilient retaining member 72 secured to the fixed cover 46 and having a curved end portion arranged to enter a corresponding recess 74 in the finger to hold the latter 30 in its operative position in the raceway. The member 72 also serves, by engagement with the finger in another recess 76 therein, to determine the proper position of the finger relatively to the shaft 44 for the block 62 to enter the recess 64 and lock the finger to the shaft when the shaft is positioned as determined by the cover 48 in the manner explained in Letters Patent No. 2,047,205.

A small plate 78 fastened on the front of an 40 angular plate 80 which is attached to the member 40 to support the upper ends of the tubes 22 serves by means of arrows and the words "First," "Second" and "Third" thereon to indicate where the upper ends of the pairs of tubes *a*, *b*, and *c*, respectively, should be connected to the member 40 in assembling the parts, and preferably also these different pairs of tubes will be differently colored to assist in tracing them, since it may be desired at times to detach one or more of them 50 in case there is any obstruction to the delivery of tacks. The plate 78 serves also as a reminder to the operator of the relation of the three fingers 58 to the three pairs of tubes, so that he will know which finger to use to prevent delivery of 55 tacks to any particular pair.

It will be understood that when tacks are to be driven by all the tacking devices the three fingers 58 are locked to the shaft 44 in alignment with the fingers 52, so that by turning the shaft 60 all the raceways may be closed, if desired, as heretofore. If the character of the work is such that the two endmost tacks of the row should be omitted, the operator releases the middle finger 58 from the shaft by sliding the appropriate block 62 to the right through engagement with its pin 68 while the cover 48 is in its normal position close above the lower end portions of the raceways, and then swings the finger downwardly until the retaining member 72 enters the recess 74 in the finger, thus closing the raceway which supplies tacks to the tubes *a*. Similarly the finger 58 at the right of the middle finger may be used, if desired, to prevent delivery of tacks to the tubes *b*, and the finger at the left of 75 the middle one may be used to prevent delivery

of tacks to the tubes *c*. While any of the three fingers is in raceway-closing position it is not disturbed in any way by movement of the shaft 44, which may be turned, if desired, to close all the raceways not already closed and thereafter to open them again. When the operator wishes to open any raceway controlled by one of the fingers 58 he swings the finger upwardly by means of its lug 66 until the retaining member 72 enters the recess 76 and then locks the finger to the shaft 10 by sliding the appropriate block 62 to the left.

Having described the invention, what I claim as new and desire to secure by Letters Patent of the United States is:

1. In a fastening-inserting machine, the combination with a plurality of fastening-inserting devices, of a plurality of raceways for fastenings, means for separating fastenings from said raceways and for delivering them to said devices, a plurality of members associated respectively with the different raceways for preventing the passage of fastenings along the raceways when the members are in operative positions, a device for moving said members as a unit into and out of operative positions, and means movable by the operator relatively to said members into position to prevent said device from thus acting on one of them when it acts on the others. 15

2. In a fastening-inserting machine, the combination with a plurality of fastening-inserting devices, of a plurality of raceways for fastenings, means for separating fastenings from said raceways and for delivering them to said devices, a plurality of members associated respectively with the different raceways for preventing the passage of fastenings along the raceways when the members are in operative positions, a shaft along which said members are arranged, said shaft being rotatable to move the members as a unit into and out of operative positions, and means 30 for disconnecting one at least of said members from the shaft at the will of the operator to permit it to remain in operative position regardless of rotation of the shaft. 35

3. In a fastening-inserting machine, the combination with a plurality of fastening-inserting devices, of a plurality of raceways for fastenings, means for separating fastenings from said raceways and for delivering them to said devices, a plurality of fingers associated respectively with the different raceways for preventing the passage of fastenings along the raceways when the fingers are in operative positions, a shaft extending transversely of the raceways and along which said fingers are arranged, said shaft being rotatable to move the fingers into and out of operative positions, and a member movable to lock one of said fingers to the shaft to turn therewith or to unlock it and thus permit it to remain in operative position regardless of rotation of the 40 shaft. 45

4. In a fastening-inserting machine, the combination with a plurality of fastening-inserting devices, of a plurality of raceways for fastenings, means for separating fastenings from said raceways and for delivering them to said devices, a plurality of fingers associated respectively with the different raceways for preventing the passage of fastenings along the raceways when the fingers are in operative positions, a shaft extending transversely of the raceways and along which said fingers are arranged, said shaft being rotatable to move the fingers into and out of operative positions, a member for connecting one of said fingers to the shaft or for disconnecting 50 55 60 65 70 75 80 85 90 95 100

necting it therefrom to permit it to remain in operative position regardless of rotation of the shaft, and a device for maintaining that finger in operative position when it is disconnected from the shaft.

5. In a fastening-inserting machine, the combination with a plurality of fastening-inserting devices, of a plurality of raceways for fastenings, means for separating fastenings from said raceways and for delivering them to said devices, a plurality of fingers associated respectively with the different raceways for preventing the passage of fastenings along the raceways when the fingers are in operative positions, a shaft extending transversely of the raceways and along which said fingers are arranged, said shaft being rotatable to move the fingers into and out of operative positions, a member slidably movable lengthwise of the shaft to lock one of said fingers to the shaft or to unlock it and thus permit it to remain in operative position regardless of rotation of the shaft, and a resilient member for maintaining that finger in operative position when it is unlocked.

6. In a fastening-inserting machine, the combination with a plurality of fastening-inserting devices, of a plurality of raceways for fastenings, means for separating fastenings from said raceways and for delivering them to said devices, a plurality of members associated respectively with different raceways for preventing the passage of fastenings along the raceways when the members are in operative positions, a device for moving said members as a unit into and out of operative positions, and means movable by the operator relatively to said members into position to prevent said device from thus acting on one or more of them selectively when it acts on the others.

7. In a fastening-inserting machine, the combination with a plurality of fastening-inserting devices, of a plurality of raceways for fastenings, means for separating fastenings from said raceways and for delivering them to said devices, a

plurality of fingers associated respectively with different raceways for preventing the passage of fastenings along the raceways when the fingers are in operative positions, a shaft extending transversely of the raceways and along which 5 said fingers are arranged, said shaft being rotatable to move the fingers into and out of operative positions, means for disconnecting one or more of said fingers from the shaft selectively at the will of the operator, and means for maintaining each finger thus disconnected from the shaft in operative position regardless of rotation of the shaft.

8. In a fastening-inserting machine, the combination with a plurality of fastening-inserting 15 devices, of a plurality of raceways for fastenings, means for separating fastenings from said raceways and for delivering them to said devices, a plurality of fingers associated respectively with different raceways for preventing the passage of 20 fastenings along the raceways when the fingers are in operative positions, a shaft supporting said fingers and rotatable to move them into and out of operative positions, and devices associated respectively with different fingers for locking 25 one or more of them selectively to the shaft to turn therewith or for disconnecting them from the shaft.

9. In a fastening-inserting machine, the combination with a plurality of fastening-inserting 30 devices, of a plurality of raceways for fastenings, means for separating fastenings from said raceways and for delivering them to said devices, a plurality of members associated respectively with different raceways for preventing the passage of 35 fastenings along the raceways when the members are in operative positions, a shaft rotatable to move said members into and out of operative positions, and means movable at the will of the operator relatively to said members into 40 position to prevent at least one of them from being operated by the shaft when the shaft is rotated to operate the others.

JACOB C. JORGENSEN.
